UNITED STATES PATENT OFFICE

JOHN J. O'BRIEN, OF WEST HAVEN, CONNECTICUT, ASSIGNOR, BY MESNE ASSIGNMENTS, OF ONE-HALF TO CALVIN C. ROBINSON, OF NEW HAVEN, CONNECTICUT

MULTIHYDRAULIC POWER DEVICE

Application filed May 8, 1928. Serial No. 276,075.

This invention relates to a hydraulic power device for utilizing great forces in moving heavy objects, and particularly for handling caissons, such as are used for building bridge pier foundations and the like, although, of course, it is not limited to use for this purpose.

It has for an object to provide a device of this character in which the immense pulling force required may be secured in a way that 10 can be used in the most effective manner for performing the work desired. As an illustration of the use of the device I have shown it in the drawings as applied for straightening up, that is to bring to a vertical position, a 15 large caisson which has become tilted in lowering it on the job. In the particular case shown the caisson was a large one that became tipped while being lowered in water and mud preparatory to building a large 20 bridge pier. The caisson was a very valuable one and as it was very large and of great weight great difficulty has been experienced in trying to straighten it and bring it back to the vertical position, as great forces were 25 required to do this and the hitherto known methods of applying them were insufficient to bring the caisson back to the proper position.

With the foregoing and other objects in 30 view, the invention consists in certain novel features of construction, combinations and arrangements of parts as will be more fully described in connection with the accompanying drawings. In these drawings,

Fig. 1 is a transverse section of a portion 35 of a river and a caisson in tipped position in the mud at the bottom of the water, and showing the method of applying and operating my improved hydraulic power device for the purpose of straightening the caisson.

Fig. 2 is a top plan view thereof on a somewhat larger scale.

Fig. 3 is a top plan view of the hydraulic 45 power device with parts in section.

Fig. 4 is an end view thereof looking from the left of Fig. 3 with parts in section.

Fig. 5 is a side elevation looking toward the bottom of Fig. 3 and on a somewhat smaller scale.

Fig. 6 is a detail of the connection between the links of the chain.

Fig. 7 is a side elevation of one of the chains.

In straightening the particular caisson 55 illustrated, the caisson 9 in question was a very large one being approximately 147 feet long, 60 feet wide and 70 feet high which became tipped to about the position illustrated in Fig. 1 as it was being lowered. In straightening this caisson chains 10 are run from a stationary anchorage 11 in the solid rock on the opposite shore, and each chain indicated at 10 is run from this anchorage over a suitable support 12 and then to the proper ele- 60 ment of my improved power device illustrated in Figs. 3 to 5. This power device is indicated as a whole by the letter (P) and is over a lighter or other similar boat 13. Chains 14 are extended in the opposite direction from this power device (P) and are connected to the caisson. The chains are very powerful 65 ones preferably comprising a plurality of flat links 15, the chain 10 being approximately 4 feet wide and 2 feet high and the links being of considerable length, the alternate links being extended in opposite directions and the pivot pins 16 extending transversely through the adjacent ends of the links. The chains 14 are in the specific embodiment shown are each 70 substantially one-half the size of the chain 10, that is, about two feet wide instead of four. It will, of course, be understood that these sizes are given merely as examples to show 75 that large forces are involved and may be handled by my device, and that the same principle may be embodied in smaller devices. If it were found desirable to connect only a 80 single chain to the object to be moved this could be connected to the abutment structure 85

90

by two or more short chains connected to the single chain and running to the abutment structure, or if the two chains 14 in the drawing were connected together they would be in effect a single connection from the abutment structure.

The chains 14 extend from the power device (P) and are connected to the caisson substantially in the manner illustrated. In making this connection bars 17 are extended transversely across the caisson at the top thereof and the chains 14 are extended across the caisson at the lower end thereof, either through transverse openings adjacent the lower end of the caisson or around outside this lower end as is preferred, and then these chains pass up the rear or top side of the caisson and are connected to the bars 17. This arrangement is used so that the heavy pull on the chains will not rupture the caisson and will have more or less the effect of a rolling hitch and will, therefore, apply the forces to the caisson in the most effective manner to bring it to the upright position without injury to the caisson. The drawings, of course, are somewhat diagrammatic, there being no attempt made to show the details of construction of a caisson, the anchorage and the like. On the drawing, I have shown two sets of these chains applied to the caisson but it will be understood a greater or less number may be used to meet the requirements of any particular job.

The principle of the hydraulic power device is shown more clearly in Figs. 3 to 5, although these figures are also somewhat diagrammatic and do not show all the details of construction and no attempt has been made to show the proper relative proportions and sizes of beams and other structures to give the strength required for the great forces involved. The device as shown comprises a pair of annular frames 18 and 19 which may be made of brass, steel or other suitable material, or they may be built up of suitable steel structural shapes to give the required strength and stiffness. As shown they are substantially I-beam shape in cross section and have their peripheral flanges connected by cross strengthening ribs 20, and mounted between the two frames are a plurality of hydraulic jacks 21, of any suitable design and having plungers 21'. A convenient manner of mounting these jacks is to place them in the spaces formed between the cross ribs 20, and the frames are made of sufficient size to carry enough jacks to give the power required. It will be understood that as liquid pressure is applied to the jacks the plungers thereof will be forced outwardly to the right as viewed in Fig. 3 and will carry the frame 18 away from the frame 19. Secured on the outer faces of the frames are suitable cross beams. The frame 18 carries cross beams 22, spaced a suitable distance apart to permit the

chains 10 and 14 to pass between them. These beams are shown of heavy I-beam construction although they may be of built up girder construction if preferred. The frame 19 carries similar cross beams 23 on the opposite side of this frame from the frame 18. These beams also carry upright cross beams 24 forming abutments for a pin 25 passing through the links of the chain 10. This chain as will be obvious, extends from the stationary anchorage 11, passes through the opening in the frame 18 and then through the frame 19 to the rear side thereof. This makes a stationary connection between the frame 19 and the chain 10, and therefore, a stationary anchorage. The chain 10, therefore, really forms a stationary support for the abutment structure 19, 23.

It will be noted the beams 22 and 23 are extended outwardly beyond the peripheries of the frames 18 and 19, and that the two chains 14 are separated sufficiently so that each of them is passed through between these beams, one on one side of the frame 18 and 19 and of the chain 10, while the other chain passes between them on the diametrically opposite side of these frames and the chain 10. On the side of the beams 22 toward the stationary anchorage these beams carry a pair of upright cross beams 26 arranged on opposite sides of the chains 14 and forming abutments for cross pins 27 extending through these chains. The beams 23 carry similar cross beams 28 arranged on opposite sides of the chains 14 and form abutments for holding pins 29 extending through the links of the chain, and these abutments are arranged on opposite sides of beams 23 from the abutments 24. The links of the chains 14 are provided with a series of transverse openings 30 for the pins 27 and 29 as will presently be described, these openings 30 being spaced from each other longitudinally of the chains, a distance approximately equal to the throw of the jacks.

It will, of course, be understood that in operation this power device is located over the lighter or boat 13 and that suitable hydraulic pumps 32, and appurtenances thereto, not shown, are carried on this lighter for operating the jacks.

The operation is as follows: The chains 10 and 14 are connected to the abutment structures at opposite ends of the jacks as shown in Fig. 3 when the plungers are retracted or in their neutral position. By abutment structures, I mean the structure involving the frame 18, beams 22 and 26, as being one abutment structure, and the other abutment structure involving the frame 19, beams 23 and cross beams or abutments 24 and 28. Now with the plungers retracted as in Fig. 3 and chain 10 connected to the left hand abutment structure involving the frame 19,

the chains 14 are connected to the right hand abutment structure involving the frame 18 by the pins 27 inserted transversely through the links of the chain and resting against the abutments 26. If preferred to secure a better bearing on these abutments, cradles 31 may be provided to increase the bearing surface for the pins and do away with a line bearing. Now if liquid is pumped into the jacks they will function and will force the frame 18 and the beams 22 and 26 to the right as viewed in Fig. 3 and will, therefore, draw the chains 14 to the right until another opening 30 is brought to the right hand side of the abutments 28 carried by the frame 19. Then pins 29 are inserted through this opening and the jacks may then be exhausted. During the exhausting of the jacks, however, the chains 14 cannot move back or to the left because they will be held by the pins 29. The abutment structure 18 is, therefore, brought back to the full line position of Fig. 3 while the chains 14 are held stationary, and then the pins 27 can be inserted in the next opening 30 which will now lie in front of the abutments 26. The jacks can now again be functioned forcing the abutment structure 18 and the associated parts to the right and drawing with it the chains 14 the same as in the first operation. It will, therefore, be apparent that the chains 14 are drawn up step by step and that after each functioning of the jacks these chains 14 are held by the pins 29 against the abutments 28 and the left hand frame 19 while the jacks are being exhausted, and they are drawn up by functioning of the jacks through the pins 27 engaging the abutments 26 carried by the frame 18.

It will be apparent from the foregoing description that an immense pull can be placed on the frames as the number of jacks may be practically any number desired depending on the weight of the structure to be displaced.

Although I have shown the device as applied to pulling on an object it may be used for lifting a caisson or other structures such as a submarine vertically after, of course, it is mounted on suitable supports, and it may also be used as a means for lowering the caisson in position.

Having thus set forth the nature of my invention, what I claim is:

1. In a device of the character described, a plurality of jacks, a pair of abutment structures arranged with the jacks between them so that expanding of the jacks will separate the structures, one of said structures being open at the center, a connection from an anchorage passing through said opening and connected to the opposite structure, and connections from the object to be moved connected to the other structure and extending

in a direction therefrom opposite to that of the first connection.

2. In a device of the character described, a pair of abutment structures, a plurality of jacks between said structures arranged to separate them on expansion of the jacks, a connection from an anchorage to the structure on the opposite side of the jacks from said anchorage, and connections from the object to be moved to the other abutment structure and extending therefrom in a direction opposite to that of the first connection. 70

3. In a device of the character described, a pair of abutment structures, a plurality of jacks between said structures arranged to separate them as the jacks are expanded, a chain extending from an anchorage to the abutment structure on the opposite side thereof from the jacks, chains extending in the opposite direction from the other abutment structure to the object to be moved, and cooperating means on the first abutment structure and the second chains to at intervals connect the second chains to said abutment structure and hold the chains while the jacks are being exhausted and the second structure again connected to said chains. 85

4. In a device of the character described, a pair of abutment structures adapted to be placed between an anchorage and an object to be moved, a plurality of jacks between said structures adapted to force them apart on expansion of the jacks, a chain extending from the anchorage to the structure on the opposite side of the jacks from said anchorage, spaced abutments on said structure on opposite sides of the chain, a pin extending transversely through the chain and resting against said abutments, a pair of chains extending from the object to be moved to the other abutment structure, spaced abutments on said structure on the opposite sides of the chains, and pins extending transversely through the chains and resting against said abutments. 95 100 105

5. In a device of the character described, a pair of abutment structures adapted to be placed between an anchorage and an object to be moved, a plurality of jacks between said structures adapted to force them apart on expansion of the jacks, a chain extending from the anchorage and connected to the abutment structure on the opposite side of the jacks from said anchorage, a pair of chains extending from the object to be moved to the other abutment structure, spaced abutments on both of said abutment structures on opposite sides of said latter chains, said latter chains being provided with transverse openings, and pins to be inserted through said 110 115 120 125 openings and rest against said abutments to hold the chains.

6. In a device of the character described, a pair of substantially annular frames, a plurality of lifting jacks mounted between said 130

frames and adapted to force them apart, a chain extending from an anchorage through one of said frames to the other, means for attaching said chain to said latter frame, a pair of chains extending from the object to be moved to the first frame on opposite sides of the first chain, abutments carried by both said frames on opposite sides of said second mentioned chains, said latter chains being provided with a series of longitudinally spaced openings, and pins to extend through said openings and engage said abutments to secure the chains to said frames.

In testimony whereof I affix my signature.

JOHN J. O'BRIEN.
